UNITED STATES PATENT OFFICE.

FRANK M. ROBBINS AND JOSEPH SHERMAN HARTLEY, OF CHATTANOOGA, TENNESSEE,
ASSIGNORS TO ROSS-MEEHAN FOUNDRIES, OF CHATTANOOGA, TENNESSEE, A COR-
PORATION OF TENNESSEE.

CONVEYER CLEAT.

1,427,229.

Specification of Letters Patent. Patented Aug. 29, 1922.

Application filed January 30, 1922. Serial No. 532,746.

To all whom it may concern:

Be it known that we, FRANK M. ROBBINS and JOSEPH S. HARTLEY, citizens of the United States, residing at Chattanooga, in 5 the county of Hamilton and State of Tennessee, have invented certain new and useful Improvements in Conveyer Cleats, of which the following is a specification.

This invention relates to cleats for use 10 with conveyers for handling slabs, sawdust, shavings or other material.

An object of the invention is to provide a cleat of simple and rugged construction which may be easily and securely attached to 15 a conveyer chain. A further object is to provide a cleat which may be attached to and detached from a chain without the use of special tools or of bolts or rivets. A further object is to provide a cleat which may 20 be firmly attached to chains having links of different size or to a chain having links which have become worn in service. More specifically an object of the invention is to provide a cleat which is attached to a chain 25 by means of a removable wedge which is locked in position by means of malleable projections.

Some embodiments of our invention are disclosed in the accompanying drawings, in 30 which—

Fig. 1 is an end elevation of a cleat on a conveyer chain;

Fig. 2 is a front elevation of the same;

Fig. 3 is a plan view;

Fig. 4 is a horizontal section of the butt 35 end of the cleat, and taken on line 4—4 of Fig. 2;

Fig. 5 is a fragmentary end elevation illustrating modifications in the construction 40 disclosed in Figs. 1—4 inclusive;

Figs. 6 and 7, are respectively a fragmentary end elevation and a plan of another embodiment of the invention;

Figs. 8 and 9 are, respectively a fragmentary end elevation and a plan of another 45 embodiment;

Figs. 10 and 11 are respectively, a front elevation and a plan of another embodiment;

Figs. 12 and 13 are respectively, a front 50 elevation and a plan of a further embodiment, and

Fig. 14 is a vertical section on line 14—14 of Fig. 13.

In the drawings, the links of the conveyer chain to which the various forms of cleats are attached are designated by the character L. In the embodiment illustrated in Figs. 1 to 4 inclusive, the butt end of the main section of the cleat 1 is provided on 55 its lower face with a groove 2 for receiving one side of a link L. The upper face of the main section 1 has formed therein a cylindrical surface subtending an arc of approximately 90° which provides a link receiving seat 3 for the reception of the opposite side of the link L. Adjacent the seat 3 the main section is provided with an approximately vertical wall 4, a second wall 5 being spaced 60 therefrom and located near the end of the cleat. The walls 4 and 5 define a recess or slot across the end of the cleat, the bottom surface of the recess being formed by the surface 6 which connects the walls 4 and 5. A clamping member 7 in the recess has a 65 seat 8 which cooperates with the seat 3 of the main section to form a link groove. The member 7 is locked in position by means of malleable lugs 9 formed thereon which may be bent over to lie in recesses 10 formed in 70 the adjacent portion of the main section 1. 75

In the embodiment of our invention illustrated in Figs. 1—4 inclusive, the walls 4, 5 are undercut to form a dovetail recess and the wall 5 is inclined to the axis of the link 80 recesses, thus providing a tapered recess or slot. The member 7 has a corresponding dovetail wedge shape conforming to the shape of the recess. The contacting surfaces of the removable member and the cleat 85 may be smooth as shown in Fig. 2, or if desired these surfaces may be corrugated as shown in Fig. 5. Fig. 5 also illustrates a further modification in that the member 7' does not encircle substantially one half of 90 the link L but terminates substantially at 95 the upper surface of the main section of the cleat 1.

The cleat shown in Figs. 6 and 7 is similar in construction to that above described, 100 but the positions of the malleable lugs and recesses have been reversed. In this form the lugs 9' are located on the end of the main section 1' and the cooperating recesses are formed in the adjacent surface of the member 7'. As herein shown the cleat 1' has 105 been applied to a link L which has a span between the opposite sides of the link which

is greater than the distance between the recess 2 and the seat 3. Due to the taper of the walls 4, 5, the wedge member 7² holds the cleat firmly to the link L even though the link is not perfectly seated on the cleat. As will be obvious this construction also permits the cleat to be firmly attached to links having side portions of a radius slightly greater than that of the link receiving seats.

10 In the form illustrated in Figs. 8 and 9, the walls 4', 5' are not tapered, but the lower face of the recess has formed thereon a tapered dovetail 6' which is engaged by a correspondingly shaped recess in the lower face 15 of the member 7³. As with the forms previously described, this cleat may be firmly attached to links of somewhat different size in view of the taper of the cooperating parts on the member and the main section of the 20 cleat.

Figs. 10 and 11 illustrate a universal cleat 12, that is one which extends to both sides of the conveyer chain. A chain receiving recess 13 and a link seat 14 are formed respectively in the lower and upper surfaces of the cleat. Adjacent the seat 14, the main section of the cleat is provided with a transverse recess of tapered dovetail construction for the reception of a locking wedge 15 upon 30 which are formed malleable lugs 16 which may be engaged in recesses 17 formed in the cleat. Obviously the height and thickness of the main section of the cleat are so proportioned that the cleat may be slipped into a chain link and then rotated through 90° position for attachment. It is also obvious that in place of using a form of wedge member 12 similar to that illustrated in Figs. 1-4 inclusive, attaching means constructed 40 as shown in Figs. 5-9 inclusive might be used.

A further form of universal cleat embodying our invention is illustrated in Figs. 12-14 inclusive, in which the main section 45 of cleat is designated by the numeral 18. On its rear face the main section 18 is provided with an extension 19 which terminates in a vertical surface passing substantially through the center line of the cleat. The 50 upper and lower portions of the extension 19 are provided with link receiving seats 20 and 21, respectively. Upon the opposite side of the center line of the cleat, the main section 18 is provided on its rear face with a tapered dovetail projection 22 having a notch 23 formed therein near its outer end. The cleat is held to a chain link L by means 55 of a member 24 which has formed in its lower surface a tapered dovetail recess by 60 means of which it may be slid into position along the back of the main section 18. The member 24 is provided with upper and lower link seats 25 and 26 which cooperate respectively with the seats 20 and 21 to form link 65 recesses. The outer end of the member 24

is provided with a malleable projection 27 which may be bent into the notch 23 to lock the member 24 in position.

While we have described some embodiments of our invention it is to be understood that the invention is not to be limited thereby as many changes may be made in the various parts, their relative location, size and proportion.

What we claim is:

75 1. A conveyer cleat comprising a main section provided with a link receiving surface, a dovetail seat formed on said main section, a member for holding a link on said surface and provided with dovetail surfaces 80 cooperating with said dovetail seat, and means for locking said member to said main section, said means comprising malleable lugs on one of said parts and cooperating recesses on the other of said parts.

2. A conveyer cleat comprising a main section provided with a surface for receiving a chain link, walls on said main section defining a tapered dovetail, a member having walls defining a tapered dovetail engageable 90 with the tapered dovetail of said main section and provided with a face adapted to hold a link on said surface, and a recess and malleable projection on said main section and said member for locking said member 95 in position.

3. A conveyer cleat comprising a main section provided with a surface for receiving a chain link, walls on said main section defining a recess across said main section and 100 adjacent said surface, a member in said recess and adapted to hold a chain link on said surface, and malleable means for locking said member in said recess.

4. A conveyer cleat comprising a main 105 section provided with a surface for receiving a chain link, walls on said main section defining a recess across said main section and adjacent said surface, a member in said recess and adapted to hold a chain link on 110 said surface, means for locking said member to said main section, said means comprising malleable lugs on one of said parts and cooperating recess on the other of said parts.

5. A conveyer cleat comprising a main 115 section provided with a link receiving groove formed in one face thereof, walls on the opposite face of said main section defining a recess extending across said main section, a seat for the opposite side of a chain link adjacent said recess, a clamping member in said recess and means for locking said clamping member to said main section.

6. A conveyer cleat comprising a main section provided with a link receiving groove 125 in its lower face, walls on its upper face defining a recess across said main section, a link receiving seat adjacent said recess, a member in said recess adapted to hold a link on said seat, and malleable means on said 130

member adapted to be bent into engagement with said main section to hold the parts assembled.

7. A conveyer cleat comprising a main section provided with a link receiving recess in its lower face and a link receiving seat on its upper face, walls on said main section defining a tapered recess, a member in said recess adapted to engage a chain link to hold it on said seat, malleable means on said member, and a recess formed in said main section and into which said malleable means is adapted to be bent to hold the parts assembled.

15 8. A conveyer cleat comprising a main section having a link receiving seat thereon, walls defining a recess across said main section, a member in said recess and provided with a surface adapted to encircle a portion 20 of a link to hold the same to said seat, and malleable means on said member for locking the same to said main section.

9. A conveyer cleat comprising a main section having a link receiving groove in its lower face and a link receiving seat on its upper face, walls on the upper face of said main section defining a tapered dovetail recess extending across the same, a wedge member in said recess adapted to hold a link

on said seat and means for locking said member to said main section.

10. A conveyer cleat comprising a main section having a link receiving groove in its lower face and a link receiving seat on its upper face, walls on the upper face of said main section defining a tapered dovetail recess extending across the same, a wedge member in said recess adapted to hold a link on said seat, and means for locking said member to said main section, said means comprising a recess on one of said parts and malleable lugs on the other of said parts.

11. A conveyer cleat comprising a main section having a link receiving groove in its lower face and a link receiving seat on its upper face, walls on the upper face of said main section defining a tapered dovetail recess extending across the same, a wedge member in said recess adapted to hold a link on said seat and means for locking said member to said main section, said means comprising a recess formed in said main section adjacent said member and a malleable lug on said member.

In testimony whereof, we affix our signatures.

FRANK M. ROBBINS.

JOSEPH SHERMAN HARTLEY.
